D. Russel,

No Printed Specification Availal

Reciprocating Saw Mill,

Patented Oct. 27, 1835.

David Russell
Letters Patent

The Schedule referred to in these Letters Patent and making part of the same, containing a description in the words of the said David Russell himself of his improvement in the "Portable saw Mill."

Be it known that I David Russell of the town of Tuscaloosa in the County of Franklin & State of Alabama, have made a new and useful improvement in the useful arts, being a machine for sawing timber, called "Russell's portable saw Mill", which is described as follows, reference being had to the annexed drawings of the same, making part of this Specification.

A, represents the frame, constructed about 15 feet long, 7 feet wide, & 10 feet high of any convenient number of pieces of timber of sufficient strength and well braced by diagonal braces - B, B, two joints of the frame, each about 10 feet long, placed at the ends thereof, and may be one or more as required. C, C, Two bottom joints supporting the machine, and may be turned up out of the way when the Machine is to be moved from place to place. D, D, Four cast wheels for moving the machine - E, E, Rail ways plated with iron for the carriage to run upon. F, The carriage made in joints in such a manner that it may be lengthened or shortened at pleasure, having rollers on the under side turning on the rail-ways and having cogged segments or such on its under sides into which the pinions work for moving it. G, G, Head & tail blocks on which the timber to be sawed rests and is secured. H, the pinions before mentioned working into the racks of the carriage, which pinions are fixed on the axle K, on the end of which is a drum & long wheel M, N, the saw connected to a piston rod O passing through an aperture in the cap piece of the frame and connected with two springs P, P. The saw works vertically between guides Q, Q, the lower slide R, R, sliding up & down on the guides. The lower end of the web is connected to the crank of the fly wheel by the piston rod O.

The gearing consists of a horizontal cog wheel I about 4 feet in diameter fixed on a vertical shaft U , which is turned by a horse attached to the lever W , of the shaft. A pinion M on the end of a horizontal shaft z , works into the horizontal cog wheel, by which the horizontal shaft is turned, on the end of which is a pulley on band wheel Y , 5 feet in diameter, around which passes a band X leading to the pulley a on the axle b of the fly wheel. On the horizontal shaft is another pulley C two feet in diameter around which passes a band leading to the drum on the cog wheel shaft for running the carriage back. On the other end of the fly wheel shaft is another crank f to which is attached a connecting rod g which is connected to an elbow h turning on a journal, on the end of which elbow is attached the feed hand e working in the cog wheel for feeding the machine.

Operation.—The carriage is run back, the log rolled upon the head and tail blocks and secured by the dogs—the machine is put in motion—the feed hand e dropped into the cog wheel—the horizontal cog wheel turns the pinion on the end of the horizontal shaft which is turned with the pulley theron and the band passing around it turns the pulley and shaft of the fly wheel which turns the cranks on its shaft. One of the cranks works the saw up and down with the aid of the springs, while the other crank at the same time operates the feed hand—this turns the cog wheel which turns the shaft and pinions—thus passing into the racks of the carriage bring the carriage forward with the log to be sawed. When the log is passed through from end to end the hand is lifted from the cog wheel which runs the carriage back, the hand is again dropped into the cog wheel and the operation continued till the log be entirely sawed—the machine is stopped. This machine may be propelled by bands or by cogged gearings of wood or iron, and may be made double or single to drive one or more saws or gangs of saws, by water, steam or horse power, and may be portable or fixed on a base to suit the convenience of the builder.

What I claim as my invention and which I desire to secure
by Letters Patent, consists in the combination and arrangement
of the several parts of the before described Straw Mill.
